LOCK STRUCTURE FOR AUTOMOBILE
DOORSEdward D. Dall, Waukegan, Ill., assignor to
Walter F. Wright, Cleveland, Ohio

Application September 5, 1936, Serial No. 99,544

6 Claims. (Cl. 70—264)

My invention relates to locking structure for controlling the locking of automotive vehicle doors and may be readily incorporated in locking controlling systems such as disclosed in my co-pending application Serial No. 655,180, filed February 4, 1933, Patent No. 2,109,997, dated December 21, 1937, or in my copending application Serial No. 716,306, filed March 19, 1934, Patent No. 2,135,967, dated November 8, 1938.

10 The invention may also be considered as an improvement over or addition to the locking controlling structure disclosed in my copending application Serial No. 66,149, filed February 28, 1936, Patent No. 2,162,702, dated June 20, 1939.

15 In these various locking systems referred to locking or unlocking of all of the doors of a vehicle is controllable by manipulation of a master lock usually located on the front right door of the vehicle, but in these systems unlocking of a door 20 by manipulation of the inner handle mechanism is possible even though the door has been locked against opening thereof from the outside. It may however, be very desirable that, when the doors have all been locked against opening from the 25 outside, the doors will also be locked against opening by manipulation of the inside handle mechanism particularly when it is desired to prevent occupants as for example children from opening any of these doors from the inside and 30 the important object of this present invention is therefore to provide structure and arrangement which will prevent such opening of the doors from the inside.

35 A further important object is to provide an arrangement so that by the omission or addition of a simple structural part a door may be held locked against opening by its inner handle mechanism after locking thereof by the master lock or may be opened by manipulation of the inside handle mechanism.

40 The various features of my invention are shown incorporated in the structure disclosed on the drawings in which drawings:

Figure 1 is the outer side elevation of a master lock and the inside handle mechanism associated therewith;

Figure 2 is an outside elevation of a remote lock for cooperation with and control by the master lock of Figure 1;

50 Figure 3 is a transverse section of a stile between adjacent doors showing the transmission means for transmitting control movement of the master lock to remote locks;

Figure 4 is a section on plane IV—IV Figure 1;

55 Figure 5 is a side elevation of the roll-back

actuating cam member in the lock of Figure 1; and

Figure 6 is a side elevation of the roll-back member of the lock of Figure 1;

Figure 7 is a plan view of a slide link forming 5 part of the lock structure.

The lock structure to which I have shown my invention applied is substantially that disclosed in my copending application Serial No. 66,149, filed February 28, 1936. The master lock structure shown on Figure 1 comprises a supporting plate 1 having the outer flange 2 thereon provided with the opening 3 for passage of the beveled latch bolt head 4 secured to the plate 5 slideable on the supporting plate 1 and guided by a post 6 10 extending from the supporting plate through the longitudinal slot 7 in the latch plate. A spring 8 engages against the inner end of the latch bolt head and tends to hold the latch structure in its outer latching position. The latch plate at its 15 inner end is widened and has rearwardly projecting guide flanges 9 and 10 engaging the supporting plate 1.

Below the latch bolt structure and adjacent to the flange 2, a cover plate 11 is spaced a distance 20 from but secured to the supporting plate, the roll-back member 15 and the roll-back actuating cam member 17 being aligned in this space, the cam member having the rectangular axial passage 18 for receiving the rectangular shank 19 25 extending from the outer door handle (not shown), while the roll-back member has a cylindrical passage 21 through which the handle shank extends, the cam member having a tooth 22 for cooperation with an abutment lug 23 extending 30 from the roll-back member.

Slidable and swingable on the supporting wall 4 below the latch bolt structure is a retractor bar 24 having a pin 25 at its outer end extending through a guide slot 26 in the wall 4 parallel with 40 the movement of the latch bolt structure. An arm 27 extends upwardly from the roll-back member in alignment with the outer end of the retractor bar so that when the roll-back member is rotated in clockwise direction the retractor bar will 45 be shifted longitudinally, and when the retractor bar is in normal position its inner end will be in front of the lower flange 10 of the latch bolt plate 5 so that the bar may communicate the rotation of the roll-back member to the plate 5 50 for retraction of the latch bolt structure. The roll-back member is rotated in clockwise direction when the handle shank is rotated in the same direction as the tooth 22 on the cam member 17 55

then engages with the lug 23 on the roll-back member.

Inwardly of the roll-back member and cam member, a pin 28 is journaled in the wall 1 and cover plate 11 and is secured to a cam lever 29 and a cam arm 30, the cam lever being in the plane of the cam member 17 and the cam arm being in the plane of the retractor bar 24 so that, when the cam member 17 is turned in counterclockwise direction by rotation of the handle shank 19, the cam tooth 22 will engage the cam edge 29' of the cam lever for clockwise rotation of the cam lever and the pin 28, and engagement of the cam arm 30 with the underside of the retractor bar 24 for upward swing of the bar about its pivot pin 25 to carry the end of the bar above the end of the latch bolt flange 10 so as to free the retractor bar from the latch bolt structure and to prevent retraction of the latch bolt structure when the retractor bar is shifted inwardly by clockwise turning of the roll-back member. A spring 31 mounted on the supporting wall 1 engages with its end against a push rod 31' which rod at its lower end abuts the shoulder 32 on the retractor bar and tends to hold this bar down in its normal position against the stop projection 33 on the plate 1. Below the cam lever 29 is a locking lever 34 pivoted at its upper end on a post 35 extending from the supporting wall 1, the lower end of the locking lever being in the path of a cam 36 carried by a shank or bar 37 which is journaled in the extension 38 depending from the wall 1. The shank or bar 37 extends to the outside of the door on which the lock structure is applied and the turning of the shank is preferably controlled by a suitable key lock, preferably of the cylinder and tumbler type. The locking lever 34 has a stop shoulder 39 for cooperating with the shoulder 40 on the lower end of the cam lever 29. On Figure 1, the lock structure is shown in unlocked condition, the shank 37 having been turned to engage the cam 36 with the locking lever 34 so as to withdraw the shoulder 39 from the path of the cam lever. When it is desired to lock the latch bolt structure against retraction by the retractor bar 24, the key is first turned to cause the cam 36 to be swung away from the lower end of the lock lever 34 so that the lever may be swung upwardly by a spring 41 to bring its shoulder 39 into the path of the cam lever. The shank 19 is then turned by the outer handle a short distance in counterclockwise direction for engagement of the cam member 17 with the cam lever 29 for clockwise rotation of the cam lever and upward swing of the retractor bar to its locking position, that is, to a position which frees it from the latch bolt structure. As the cam lever is turned, its lower end glides past the lever 34 so that the lever may be swung upwardly by the spring 41 for setting of its shoulder 39 in the path of the shoulder 40 to thereby lock the cam lever in set position. The latch bolt structure cannot now be retracted from the exterior of the door on which the lock structure is applied as clockwise turning of the shank 19 by its handle will result only in longitudinal inward shift of the retractor bar past the abutment flange 10 without retraction of the latch bolt. To unlock the structure to permit retraction of the latch bolt by the outer handle, the key is turned to engage the cam 36 with the locking lever for downward swing of the lever and withdrawal thereof from the cam lever 29, the spring 31 then returning the retractor bar to normal or unlocking position, the downward swing

of the retractor bar, by its engagement with the cam arm 30 causing the cam lever 29 to be swung back to its normal position. Now upon turning of the outer handle in clockwise direction, the roll-back member 15 will shift the retractor bar inwardly against the abutment flange 10 and the latch bolt structure will be retracted.

Besides controlling the retraction of the latch bolt in the master lock (Figure 1), the cam lever 29 functions also to control the retraction of the latch bolt in remote locks, that is, locks on the other doors of the vehicle, as for example, the lock shown in Figure 2. Between the wall 1 and the locking lever 34, a plate 42 is slidable and carries at its outer end a pin 43 which projects through a passage 44 of the flange 2. The hair pin spring 41 which is coiled about the post 35 engages at its front end with the locking lever 34 and tends to swing it upwardly and as its rear end engages the abutment 45 formed on the plate 42, this spring tending to normally hold the plate 42 shifted inwardly with the outer edge of the guide slot 46 of the plate abutting the post 35. When the outer handle of the vehicle lock is turned in counterclockwise direction to swing the cam lever 29 for releasing the retractor bar 24 from the latch bolt structure, the lever 29 at its lower end also abuts against the inner end of the pin 43 and the pin and the plate 42 are shifted outwardly. As will be explained more in detail later, such outward shift of the pin 43, acting through transmission mechanism provided in the stiles or posts between adjacent doors, will cause inward movement of pins in the remote locks for swing of retractor bars in such remote locks away from the latch bolt structure therein so that at such remote locks the latch bolt structure cannot be retracted by turning of the outer handle.

When the key controlled cam 36 of the master lock is turned for release of the locking lever 34, the cam lever 29 is locked by the locking lever in set position to hold the plate 42 and pin 43 in outer position, and when the cam 36 is reset to swing down and release the locking lever from the cam lever the spring 41 will shift the plate 42 inwardly to cause retraction of the pin 43 and thereby release the locking means in the remote locks so that these locks can again be opened from the exterior.

For controlling the latch bolt operation from the inside of the door on which the lock structure is applied, a supporting plate 47 is secured to the door inwardly of the latch bolt supporting structure and another plate 48 is spaced from and secured to the plate 47. These plates journal the shank 49 of an inner door handle 50 and the shank, between the plates, carries an arm 51 connected with one end of a bar 52. Instead of connecting the other end of the bar 52 directly with the latch bolt as, for example, in the arrangement shown in my copending application Serial No. 66,149, filed February 28, 1936, I connect this end of the bar with a link in the form of a plate 53 slidable between the latch bolt plate 5 and the supporting plate 1 and having the longitudinal slot 7' receiving the guide post 6. The slide plate 53 engages against the rear face of the latch bolt plate 5 and has upper and lower guide flanges 54 and 55 engaging with the supporting plate 1 to leave space between the plate 53 and the supporting plate 1 for the retractor bar 24 when it is longitudinally shifted while in its upward swung position. The shape

and contour of the side plate 53 is clearly shown on Figures 1 and 7.

The spacer flange 55 of the plate engages the inner side of the lower spacer flange 10 on the 5 latch bolt plate 5. The rear end of the slide plate beyond the rear end of the supporting plate 1 has a longitudinally extending slot 56 receiving the pin 57 at the adjacent end of the bar 52 extending from the inner handle mechanism. The outer end of the slide plate extends 10 in front of the retractor bar 24 and has a longitudinally extending slot 56' which receives the pin 25 which pivots the retractor bar so that, when the inside handle 50 is swung downwardly to 15 exert pull on the bar 52, the slide plate 53 will be shifted rearwardly for rearward shift of the retractor bar, and if during such shift the retractor bar is in unlocking position it will engage the flange 10 of the latch bolt plate 5 and 20 the latch bolt structure will be retracted. But, if during rearward shift of the plate 53 the retractor bar is in upward swung or locking position, the bar will merely glide past the flange 10 and the latch bolt will not be retracted so 25 that the latch bolt is locked against retraction by the inside handle and the door cannot be opened from the inside.

When the inner handle 50 is swung a distance in counterclockwise direction, the latch bolt structure 30 will be locked against retraction by the outer door handle and at the same time the pin 43 will be shifted outwardly for locking of the remote lock latch bolts against retraction by their outer handles. This is accomplished by 35 means of a slide plate 53 guided for longitudinal inward and outward movement on the wall 1 by pins 59 engaging in slots 59'. The slide plate at its rear end has the upward extension 58' in the path of the head 57' on the pin 57 so that 40 when the bar 52 is pushed by the counterclockwise rotation of the inner handle the head 57' will abut the extension 58' and the slide plate 53 will be shifted forwardly to carry its end 60 into position below a finger 27' on the roll-back 45 45 so that the roll-back member cannot be turned by the outer handle but will be dogged and therefore the latch bolt cannot be retracted. Also during forward movement of the slide plate 53 a shoulder 61 thereon engages with the inner end 50 of the plate 42 and this plate will be shifted outwardly for outward projection of the pin 43 and consequent locking of the latch bolts of the remote locks against retraction by the outer handles.

55 Ordinarily when the inside handle mechanism is operated for locking in the master lock, the cam 36 will be in position for holding the locking lever 34 down so that the cam lever 29 will be in its normal position. Then when the dogging plate 58 is shifted inwardly by operation 60 of the inside handle the upper edge thereof will come into position below the stop lug 62 on the cam lever 29 thus locking the cam member 17 and the outside handle against counterclockwise movement, and as the roll-back member 15 is dogged against movement by the dogging plate 58 the outside handle will be rigidly held against any rotational movement. Should attempts be 65 made to lock by operation of the inside handle when the master lock has already been set to locking position by counterclockwise rotation of the outer handle and clockwise rotation of the cam lever 29, then the abutment 62 on the cam lever will be in front of the outer end of the 70 75

dogging plate 58 and the inside handle cannot be actuated.

As has already been explained hereinbefore, when the master lock is in locked condition, during which time the retractor bar 24 is swung upwardly clear of the latch bolt structure, the latch bolt cannot be retracted by operation of the inside handle 50, as the pull on the bar 52 upon downward swing of the inner handle 50 will shift rearwardly the plate 53 and the retractor bar 24 pivoted thereto and as the retractor bar is in its raised position inward shift thereof will not affect the latch bolt and the bolt remains latched, so that the door cannot be opened from the inside.

On Figure 2 is shown lock structure slightly modified for service on remote vehicle doors, that is, the doors other than the door on which the master lock is applied. The structural parts in the lock of Figure 2 which are the same as the 20 structural parts of Figure 1, have been given the same reference numerals. In the structure of the remote lock, the cam element 17 of the master lock structure has been omitted and the roll-back member 67 is mounted on the shank or stem 68 of the outer door handle so that upon turning of the handle the roll-back is directly rotated for engagement with the end of the retractor bar 24 whose inner end is normally in position in front of the abutment flange 10 of the latch bolt structure plate 5. Locking of the latch bolt structure against retraction by the outer handle is accomplished by freeing the retractor bar 24 from the latch bolt, such movement resulting from the inward shift of the pin 43', such inward shift 35 being, as has already been explained, caused by the outward movement of the pin 43 in the master lock by way of transmission mechanism within the posts or stiles between adjacent doors, as will be presently more explained in detail.

In place of the cam lever 29 in the master lock shown in Figure 1, a lever 70 is provided in the remote lock and supported by a pin 71. At its inner end this lever has the abutment extension 72 for engaging with the under edge of the retractor 45 bar 24 so that when the lever is swung in counterclockwise direction the retractor bar will be swung upwardly to raise its inner end above the abutment flange 10 of the latch bolt structure. At its lower end, the lever has a notch 73 inwardly of which the lower edge of the lever forms an inclined or cam surface 74, and outwardly of which notch the lever has the abutment finger 75, the notch normally receiving the abutment extension 76 deflected from the plate 42 from 50 55 which the finger or pin 43' extends.

Figure 2 shows the parts in unlocked position, the pin 43' being held in projected position by the force of a hairpin spring 77 coiled about the post 35 with one end anchored around the edge 60 of the wall 1 and the other end engaging the abutment projection 45 on the plate 42. In such normal position the abutment 76 on the plate 42 is within the notch 73 and against the finger 75 on the lever 70 to hold this lever released from 65 the retractor bar 24 which seats against its rest 33, so that when the door handle is turned in clockwise direction the retractor bar will engage with the latch bolt structure for retraction thereof. However, should the pin 43' be shifted inwardly, the abutment 76 on the plate 42 will engage with the cam edge 74 of the lever 70 and the lever will be swung upwardly for engagement of its abutment 72 with the retractor bar to swing the retractor bar to locking position, 70 75

that is, free from the latch bolt structure so that when the door handle is then turned the retractor bar will merely shift longitudinally but will not retract the latch bolt. Upon release of the pin 43', the spring 77 will shift the plate 42 back to its outer position so that the engagement of the abutment 76 with the finger 75 on the lever 70 will swing the lever downwardly for release of the retractor bar, which bar is then swung down to its normal position by the force of the spring 31 so that the latch bolt may now be withdrawn by rotation of the door handle. Upon release of the door handle, the spring 31 will shift the bar outwardly to its normal position and the spring 8 will shift the latch bolt structure back to its latching position.

The inside handle mechanism for the remote lock shown in Figure 2 and its connection with the lock mechanism may be the same as that for the master lock shown in Figure 1, the slide plate 53 being connected at its rear end with the bar 52 of the inside handle mechanism, and the slide plate at its front end receiving the pivot pin 25 for the retractor bar 24. When the lock is in its unlocked condition as shown in Figure 2, operation of the inside handle will shift the slide plate 53 rearwardly and with it the retractor bar 24 and as the bar is in its lower or unlocked position it will engage the lower flange 10 on the latch bolt plate 5 so that the latch bolt will be withdrawn.

If the pin 43' has been shifted inwardly for swinging of the lever 70 and upward swinging of the retractor bar 24 to locking position, then rearward shift of the slide plate 53 by the inside handle would not affect the latch bolt and the door would remain latched.

The transmission of the movement of the pin 43 of the master lock to the pin 43' of the lock of the door adjacent to the master lock door is shown on Figure 3. At the sides of the post or stile 78 between the adjacent doors, levers 79 and 79' are pivoted at their outer ends by pins 80 for horizontal swing, a transmission bar 81 slidably on the rear wall of the stile being interposed between the ends of the levers. The lever 79 is in alignment with the pin 43 of the master lock structure and the lever 79' is in alignment with the pin 43' of the remote lock so that when the pin 43 is shifted outwardly and the master lock is locked, the pin 43' will be shifted inwardly for locking of the respective latch bolt against unlatching movement by the outer handle.

The movement of the transmission lever 79 controlled by the master lock pin 43 may be communicated to a suitable lever 85 pivoted at 86 to the stile 78 and the movement of the lever transmitted by a cable 87 to transmission means between the adjacent doors on the opposite side of the vehicle so that all the remote door locks may be controlled by operation of the master lock in a manner such as is clearly disclosed in my copending applications referred to herein.

The provision for preventing opening of the vehicle doors by operation of the inside handle is very desirable. For example, suppose that the driver of the vehicle wants to prevent occupants such as children from opening the doors from the inside. With the structure disclosed, the driver will operate the inside handle on the front right door to lock the master lock, and the projection of the pin 43 from the master lock 78 also effects locking of the latch bolts at the

other or remote doors, such locking with the structure shown involving the swinging of the retractor bars free of the latch bolt structures. Although the inner door handles on the remote doors may be swung, the doors cannot be unlatched and the occupants cannot get out of the vehicle through the remote doors. Should the driver desire to leave the car and keep the occupants locked therein, he will first turn the key at the master lock to release the lock lever 10 34 and will then turn the outer handle of the master lock a short distance in counterclockwise direction for upward swinging of the master lock retractor bar and outward shift of the pin 43 for upward swinging of the retractor bars in the remote locks and then when the lock plate 34 locks the pin 43 in projected position all the locks on the vehicle are held in locked position and none of the doors can be opened from the inside by operation of the inner handle.

I provide a simple expedient and means for adapting any one or all of the locks for retraction of the latch bolt by operation of the inside handle when the latch bolt is locked against retraction by the outside door handle. The means shown comprises a screw 100, best shown in Figure 4, this screw threading into the latch bolt plate 5 from the rear thereof and having its head 101 engaging in an opening 102 through the slide plate 53, so that when the inner handle is operated for pull on the bar 52, the latch bolt is directly retracted and the retractor bar 24 also shifts inwardly with the link 53 and whether the retractor bar is in locking or unlocking position is not material as the bar and latch bolt are moved together. In order that the latch bolt may readily retract inwardly, as when an open door is slammed shut, the opening 102 is elongated so that the latch bolt may shift inwardly without moving the slide link 53. When the roll-back of a lock is swung by the outer handle for retraction of the latch bolt by the retractor bar, the slide link 53 does not move with the retractor bar on account of the elongated slot 56' which receives the pin 25 on the retractor bar, and the link 53 does not move with the latch bolt on account of the elongated slot 56 so that the inside handle mechanism is not disturbed.

In locking installations where it is desired that the doors may be opened at any time by operation of the inside handle means, the screws 100 will be applied, but when such inside opening of the doors is not desired, the screws are omitted from the locks. In automobiles it may be desirable to have only the rear doors locked against unlatching by the inside handle means and in such case the screws will be omitted from the locks on the rear doors.

I have shown a practical and efficient embodiment of my invention but I do not desire to be limited to exact construction, arrangement and operation shown and described as changes and modifications may be made without departing from the scope of the invention.

I claim as follows:

1. In a vehicle body having a door, a lock structure for holding the door closed, an outside handle on the door cooperable with the lock structure for opening of the door, an inside handle on the door also cooperable with the lock structure for opening of the door, and means controlled from a point on the vehicle remote from said door for setting said lock structure to prevent opening of the door by said outside handle and for preventing opening of the door by operation of the 75

inside handle while said outside handle is ineffective to open said door.

5. In a vehicle body having a door, a lock structure for the door comprising a bolt for holding the door closed, a retractor member normally positioned for movement into engagement with said bolt for retraction thereof, an outside handle and a roll-back effective upon forward movement of said handle for moving said retractor member for retraction of said bolt, an inside handle and a connection therefrom to said retractor member independently of said roll-back for movement of said retractor member to retract said bolt, and means for setting said retractor member out of bolt engaging position whereby to prevent retraction of said bolt by operation of either of said handles.

3. A locking mechanism for a door comprising a bolt for holding the door closed, an outside handle and an inside handle on said door, a link normally positioned for movement into engagement with said bolt for withdrawal thereof, an actuator element movable with said outside handle into engagement with said link for movement thereof for withdrawal of the bolt, a connection from said inside handle directly to said link independently of said actuating element for effecting movement of said link for withdrawal of said bolt, and means for displacing said link whereby both handles will be ineffective to cause withdrawal of said bolt.

4. A locking mechanism for a door comprising a bolt for holding the door closed, an outside handle and an inside handle on said door, a single link normally positioned to transmit op-

eration of either handle to said bolt for withdrawal thereof, and displacing means for displacing said link whereby both handles will be rendered ineffective to withdraw said bolt, said displacing means including a train of mechanically associated movable parts extending to a point remote from said door and there provided with an actuator.

5. In a vehicle body having a door, a lock structure comprising holding means for holding said door closed, releasing means on the exterior and releasing means on the interior of said door operably associated with said holding means and movable independently of each other for effecting release movement of said holding means for opening of the door, and means for rendering both of said releasing means unable to effect release movement of said holding means including a train of mechanically associated movable parts extending to a point in said vehicle remote from said door and there provided with an actuator.

6. In a vehicle body having a door, a locking mechanism comprising a locking member for holding the door closed, an outside handle and an inside handle on the door, a single control member normally set relative to said locking member to enable either handle to independently effect unlocking of said locking member, and setting means consisting of a train of mechanically associated movable parts extending to and controlled from a point on said vehicle remote from said door for setting said control member to render both handles unable to unlock said locking member.

EDWARD D. DALL. 35
